CLAIM

The ornamental design for suspending clip for a hangtag, as shown and described.

DESCRIPTION

FIG. 1 is a perspective view of a suspending clip for a hangtag in actual use showing my new design, with the broken line showing for illustrative purposes only and forming no part of the claimed design;

FIG. 2 is a front elevational view of the suspender shown in FIG. 1, with the suspension portion in an extended position; the rear elevational view thereof being a mirror image;

FIG. 3 is a right side view of FIG. 2;

FIG. 4 is a top plan view of FIG. 2;

FIG. 5 is a left side elevational view of FIG. 2;

FIG. 6 is a bottom plan view of FIG. 2;

FIG. 7 is a sectional view taken along the line 7—7 of FIG. 2; and,

FIG. 8 is a front elevational view showing another embodiment of FIG. 1, in which the suspension portion is in an extended position.
